GOLF CLUB HEAD

Frank L. Johnston, 3157 Chicago Ave.,
Riverside, Calif. 92507

Filed Dec. 13, 1965, Ser. No. 155

Term of patent 14 years

(Cl. D34—5)

The characteristic feature of my design resides in the particular pattern shown in full lines on the face of a conventional golf club head.

I claim:

The ornamental design for a golf club head, substantially as shown and described.
